UNITED STATES PATENT OFFICE.

LUDGER LAUZON, OF CHICAGO, ILLINOIS.

FOLDING BED AND BOAT ATTACHMENT FOR AUTOMOBILES.

Application filed March 5, 1925. Serial No. 13,332.

This invention relates to a folding bed and tent for use with certain types of automobiles commonly on the market and is adapted to be secured in the place of the usual box on 5 a runabout automobile of the type referred to.

The present invention has for its object a bed which may be set up in operative position within a minute or two of time and 10 which may likewise be folded into inoperative position in a similar amount of time.

A feature of the invention is the construction which permits the bed to fold compactly at the rear of the automobile in a not unsightly manner.

Another of the features of the invention is the manner of suspending the springs so that when the bed is folded, a clear space is 20 left above and below the bedding and springs to permit the storage of any desired articles therein.

A still further feature resides in the provision of the means for instantaneously tensioning the springs when the bed has been 25 set up.

A still further feature resides in the manner of drawing the canvas covering taut.

Another feature resides in the construction 30 which permits the bed to be removed from the automobile chassis and used as a boat.

A still further feature resides in the arrangement which permits the rear end of the structure when folded to be closed by a table 35 top which may be readily removed and used for its ordinary purpose.

Still further features and advantages will appear from time to time as the description 40 of the invention progresses. The invention will be most readily understood from a detailed description thereof, taken in connection with the accompanying drawings in which—

Figure 1 is a longitudinal section through 45 applicant's bed, in operative position showing its relation to the automobile.

Figure 2 is a plan view of the bed frame and springs in operative position with one corner broken away.

50 Figure 3 is a perspective view of the upper right corner of the arrangement in Fig. 2, showing the spring tensioning in arrangement and its relation to the bed box or frame.

Figure 4 is a section on the line 4—4 of 55 Fig. 1.

Figure 5 is a perspective view of the table used to close the rear end of the bed box when in folded condition and—

Figure 6 is a view of the rear of the bed 60 when assembled.

Referring now to the drawings in which like reference characters indicate the same parts in the several views, the line 10 indicates the outline of the rear of the top of the 65 runabout and 11 schematically indicates the portion of the runabout on which the bed rests. The bed box consists of the U-shaped ribs 12 and 13 which are joined at their free ends by means of the angle strips 14, which extend about the entire upper edge of the bed. The bed box is in two sections, the limits of 70 the two sections being defined by the ribs 13 respectively. The two sections are secured together by means of the hinges 15, each of 75 which has a leaf 16, secured to the upper rail 14 of one-half of the bed, the other leaf 17 being secured to the end of the upper rail 14 of the other half. Rivets 18 or any other desired means may be provided to secure the 80 hinge leaves to the flanges of the top rails 14.

Extending across the bed box at the left end thereof, as shown in the drawing, is an angle iron or other device 19, to which is secured one end of each of the springs 20, the other 85 end of each of the springs 20 being joined to the woven spring structure or wire mattress 21. The ends of the bar 19 may be supported in any desired manner. In the present structure the upper flange of the bar 19 90 is notched and received by a corresponding notch in the adjacent vertically extending cleat or bar 21.

Extending transversely of the bed at the opposite end thereof is a similar bar 22, to 95 which the opposite end of the woven spring structure 21 is joined through the medium of the coiled springs 23. The forward edges of the ends of the bar 22 engage the wedge or sloping surfaces 24 of the blocks 25, secured 100 to the bed frame. The surface 24 terminates at the lower end thereof in a vertical extending or slightly undercut portion against which the edge of the bar 22 rests when the springs have been brought taut.

The upper rail 14 is provided adjacent to the block 25 with the notch or recess 27 through which the end of the bar 22 may 105

pass to remove the springs from the box. Such removal is however normally prevented by means of the plate 28 slidably mounted on the upper surface of the horizontal flange of the bar 22.

It should be here stated that a covering 30, of sheet metal or like material is secured to the ribs 12 and 13 and to the top rail sections 14 in order to form a complete closure on the sides and bottom when the device is extended as shown in Fig. 1.

Between applicant's bed and the supporting surface 11 of the car are arranged the spacing blocks 31, which provide a clearance to take care of any inequalities in the supporting surface 11. Secured to the upper surface of each of the blocks 31 by means of the bolts 32 are the straps 33, the upper free ends of which are secured to the adjacent top rails 14 by means of the bolts 34. The blocks 31 together with the straps 33 form a sort of cradle in which the forward end of the bed rests, the bed being firmly secured in position by means of the bolts 34.

At 35 is shown the canvas covering for the bed. The rear end 36 of this covering may be secured to the end of the bed by curtain fasteners 37, or if desired by ropes which pass under the bottom of the bed and are secured to the rear bar 31, as by screw eye and snap fastenings. The forward end of the canvas cover 35 passes up over the top 38 of the car and is secured preferably to the forward bow by hooks or in any desired manner.

The ends of the U-shaped balelike tension member 39 are secured to the opposite sides of the bed box. The tension member 39, will, when in operative position, be folded down into the bed box. When the bed has been set up and the canvas placed in position, the bale 39 will be rotated up into the position indicated in Fig. 1, and will act to instantaneously tension the canvas 35 and retain it in a position out of the way of the occupants of the bed. The sides of the canvas covering 35 may be secured down if desired, by ropes extending under the bed or in any desired manner.

It will of course be understood that the usual mattress and bedding will be placed upon the woven spring or mattress shown at 21. Assuming now that the bed is in folded position, as indicated by dotted lines in Fig. 1, all that is necessary to set up the bed is to swing it back on the hinges 13 into the full line position, push the cross bar 22 downwardly along the inclined surface 24 to tension the springs, secure the ends of the canvas covering 35 in position as described, then swing up the bale 19 and the structure is ready for use. It has been demonstrated that this operation may be performed by two people in two minutes.

When it is desired to fold the bed, the re-

verse operation is performed. The bale 39 is turned down, the ends of the canvas 35 are removed, the bed is then folded up into dotted line position, the bedding being folded within the woven springs. Due to the lateral tension of springs 40 on each side of the hinge joint, the spring structure is maintained centrally of the bed box when folded so as to provide a space both above and below the bed and within the box for the canvas covering, luggage or any other desired articles.

The table, shown in Fig. 5, comprising the top 41 and legs 42, is employed to close the open rear end of the bed structure when in folded position. The table is so proportioned that the legs 42 will slide into the bed structure, one at each corner thereof, notches 43 being provided in the table top to receive the joints of the hinges 15. When the table has been placed in position as just explained, the leaves 44 of the hasps 45 may be turned over the staples 46, extending outwardly from the bed box, adjacent to the rear edge of the forward half, the hasp being secured into position by placing a pin through the staple or if desired, a padlock indicated at 47, may be employed.

A similar hasp structure may be employed to secure the two halves of the bed box together adjacent to their forward ends when in folded position.

If desired, the underside of the table top 41 may be provided with a plurality of spring clips 48, employed to secure plates, pans or other like articles in position. It is of course to be understood that in the process of setting up and folding the bed above described, the table just above described would necessarily have to be removed from and replaced in position and the hasp leaves 44 may be used as handles in removing the table from its position at the end of the folded bed box.

The present structure is so designed that it may be readily removed from the automobile chassis, the bed taken out and the box employed as a boat. Secured to one of the ribs 13 is a gasket 50, of fiber, rubber composition or other desired material. When the bed box is to be used as a boat, the ribs 13 will be clamped together by means of bolts 51 which pass through aligned notches or openings in the vertical flanges of the ribs 13, thus firmly securing the two halves together. The bolts 51 will not however be used when the device is merely set up as a bed. In order to remove the bed box from the chassis, it is only necessary to remove the four bolts 34 which pass through the upper end of the straps 33 and the top rail sections 14.

By simply withdrawing the sliding plates 28 at the ends of the bar 22, the bar 22 may be readily removed from the bed box. The

bar 19 at the other end of the bed may be removed in a similar manner, thereby merely unhooking the ends of the coiled springs 20—23 and 40 from the bed box, the whole 5 bed and spring structure may be readily removed to permit the bed box being used as a boat. The bed box being over six feet long, about 44" wide and having a depth of about 12", will have a supporting strength 10 in the water of approximately 1400 lbs, leaving a supporting strength of over 1250 lbs exclusive of the weight of the boat. It will be readily seen that this structure will safely support two people for the purpose of fishing 15 or the like.

If desired, the bed may be provided with pneumatic pillows which may also be used as life preservers for use with the boat.

While in the drawings and the above description a single set of details has been disclosed, it is to be understood that certain modifications are contemplated and the invention should therefore be limited only by the scope of the appended claims.

Having thus described my invention, what I claim as new and desire to secure by Letters Patent of the United States is.

I claim:

1. In a folding bed attachment for automobiles, a bed box comprising two sections hingedly joined at the tops of their abutting edges, a frame for said bed box comprising a

rail at the upper edge thereof, transversely extending ribs, an imperforate covering of sheet material forming the sides and bottom of said box on said ribs, means for snugly securing the abutting edges of said sections together and a flexible bed supporting member removably supported within said bed box.

2. In a folding bed attachment for automobiles, a bed box comprising two sections hingedly joined at the tops of their abutting edges, a flexible bed supporting member positioned within said bed box, a table having legs adapted to fit within the corners of said sections of the bed box when in folded position, the top of said table being arranged to close the open end of the folded bed box structure.

3. In a folding bed and boat attachment for automobiles, a box comprising two sections hingedly joined at the tops of their abutting edges, said box sections being generally U-shaped in cross section and formed of imperforate material, a waterproof gasket secured to the edge of one of said sections and means for snugly securing the abutting edges of said sections together with said gasket clamped therebetween.

In testimony whereof I have signed this specification.

LUDGER LAUZON.
